UNITED STATES PATENT OFFICE

PERCY R. SEWARD, OF MINNEAPOLIS, MINNESOTA

DUPLICATING PRINTING MACHINE

Application filed October 10, 1930. Serial No. 437,706.

This invention relates to duplicating printing machines and provides improved ribbon-feeding means whereby the ribbons are caused to wear longer and more evenly and uniform reprinting is produced.

Generally stated, the invention consists of the novel devices, combinations of devices and arrangement of parts hereinafter described and defined in the claims.

10 Particularly, the invention relates to duplicating machines of the type wherein the type on the segment of a rotary drum or member are brought into contact with the paper and the latter pressed against the ribbon during 15 a portion of the rotation of the drum or type carrier; and the ribbon is given a step by step feed movement during the travel or that part of the rotation of the type carrier that is between the printing actions. In duplicating 20 machines of the above character, means has hitherto been provided for giving one short feed movement to the ribbon during each printing action and, in fact, the nature of such duplicating machines has been such that 25 it has not been considered practically possible to impart either very long length movements or a plurality of short movements to the ribbon during successive printing operations. The result of this old short feed movement 30 has been that with a type cylinder say of six inches circumferential extent, extending through approximately 180 degrees, about eighteen successive movements, one between each printing operation has been required to 35 present entirely new or different ribbon surface to the type of the cylinder and from this it has further resulted that any particular letter would not be uniform. My invention provides means for imparting a plurality of movements to the ribbon between 40 each printing operation so that new or other parts of the ribbon would be presented to the type of the cylinder during five or six successive printing operations.

The invention, in its commercial form, has been designed and particularly adapted for application to a duplicating machine manufactured by the American Multigraph 50 Company of Cleveland, Ohio, and by them

designated as their No. 36, Gammeter printer.

In the accompanying drawings, which illustrate the invention, like characters indicate like parts throughout the several views.

Referring to the drawings:

Fig. 1 is a front to rear vertical section taken about centrally through a duplicating machine of the character just above indicated and illustrating the present invention applied thereto;

Fig. 2 is a fragmentary vertical section taken on the line 2—2 of Fig. 2;

Fig. 3 is a front to rear vertical section taken on the line 3—4 of Fig. 2, looking toward the left;

Fig. 4 is a front to rear vertical section taken on the line 3—4 of Fig. 2, looking toward the right; and

Fig. 5 is a fragmentary section taken on the line 5—5 of Fig. 1.

The framework of the machine is made up chiefly of a cast base 6, head plate 7 and a top tie-bar 8, which parts are rigidly connected. Journaled in axial hubs of the head plates 7 and extended through the frame is a main operating shaft 9 equipped at one outer end with an operating crank 10 for hand operation of the machine, inasmuch as the machine is especially designed as a manually-operated machine. Located adjacent to the inner faces of the head plates 7 and rigidly secured to shaft 9 for rotation therewith are spider-like head brackets 11 further tied together by rods 12 and 13. These head brackets carry a detachably applied type segment 14 that carries replaceable type 15 for the printing of letters, circulars or the like according to the set-up of the type on the segment.

The segment 14 in the machine illustrated extends through approximately 180 degrees, leaving an open space in the other 180 degrees in which is mounted ribbon rolls 16 and 17, the studs 16^a and 17^a of which are journaled in arms of the rotary head brackets 11.

The type-equipped segment 14 co-operates with a platen roller 18, the shaft 18^a of which is journaled in the base 6 and the top

of which roller works through and opens in said base. The shaft 18^a is provided at one end with a small spur gear 19 that meshes with a large annular spur gear 20 carried by 5 one of the rotary head brackets 11. The sheet of paper γ that is to be printed is fed over the platen roller 18 by co-operating lower and upper feed rolls 21 and 22, the shaft 21 of which former is journaled in the base 10 6 and is provided at one end with a spur pinion 23 that is connected to the gear 19 by a small intermediate gear or pinion 24 suitably journaled on the base 6.

The inked ribbon 25 is passed over the exposed face of the type 15 and its ends are reversely wound on the ribbon rollers 16 and 17, as best shown in Fig. 1. The studs 16^a and 17^a, respectively, are equipped with ratchet wheels 26 and 27, see Figs. 1 and 4, 20 the teeth of which are arranged for reverse ribbon-feeding actions. Reversely acting feed dogs or pawls 28 and 29, co-operate with the ratchet wheels 26 and 27, respectively.

The mechanism so far described in connection with the drawings is the structure of the so-called Gammetter printer No. 36 above further identified; and in said machine there is further an eccentrically actuated member that imparts reciprocating movements to the 25 dogs 28 and 29 during 180 degrees of movement that the printing segment is out of action and, moreover, said machine comprises a device for automatically shifting the two dogs 28 and 29 alternately into action as the 30 ribbon is wound substantially from the one roll to the other. The automatic shifting action above noted is not a part of the present invention.

The means hitherto employed for reciprocating the dogs 28 and 29 could and did impart but one step of movement, to wit: about a three-eighths inch movement to the ribbon for each complete rotation and resulting operation of the printing segment and under 45 which action, of course, the type press the ribbon against the paper sheet to be printed.

This invention, as already indicated in a general way, is directed to improved ribbon feeding means whereby a plurality of steps 50 of movement will be imparted to the ribbon for each printing operation. As a preferred means for carrying out this improved feeding movement, a cam plate 30 is rigidly secured to the inner face of one of the fixed 55 frame head plates 7. This cam plate when designed as an attachment for means now in use will be made as a separate element readily applicable to the said frame head plate; but in the designing of new machines, said 60 cam plate would naturally and preferably be cast integral with the head plate to which it is applied. As best shown in Fig. 3, cam plate 30 is provided with a profile cam-way 31 which, throughout about 180 degrees, extends concentric to the axis of shaft 9 and

throughout its other 180 degrees, is provided with a plurality of eccentrically or radially depressed and projected cam-way sections 31^a of which as shown there are three, although the number thereof might vary from two or more. As a simple and efficient means for imparting the plurality of feed movements to the ribbon for each rotation and operation of the type segment, there is provided a reciprocating plunger-acting pawl carrier shown as in the form of a flat sliding bar 32, to the intermediate portion of which the pawls 28 and 29 are pivotally attached. At its inner end, pawl carrier slide 32 is formed with an elongated loop 32^a that slides on the concentric hub 30^a of cam plate 30. To guide the outer end of pawl carrier 32 for straight-line radial movement, it is as shown, provided with a laterally projected lug 32^b that slides on a radial guide rod 33 rigidly secured to the adjacent rotary head bracket 11. Pawl carrier 32 is provided with a laterally projecting roller equipped stud 32^c.

As already indicated, the means for alternately shifting the dogs 28 and 29 into action when the ribbon is nearly wound from one roll to another is a part of the machine above identified and not here illustrated or described in detail. It is sufficient for the understanding of this case to state that one or the other of the dogs 28 or 29 will always be in action to wind the ribbon in the one direction or the other onto the receiving and off from the delivery roll. With the cam-acting device described, it is evident that between 90 each printing operation the pawl carrier 32 will be given three complete in and out movements. In the particular arrangement illustrated, outward movement of the pawl carrier will simply give the operative pawl a new grip on its co-operating ratchet wheel while return or inward movement will impart movement to the ribbon roll and hence to the ribbon. With the above described arrangement for each printing action the ribbon will, 95 for example, be given three steps of movement, each step being three-eighths of an inch and the three steps giving to the ribbon nine-eighths or one inch and an eighth of a movement for each printing operation.

Now, assuming that the extent of the printing type is approximately or slightly less than 180 degrees in circumferential extent, then completely new ribbon surface will be exposed to all printing operation of the entire segment following each five printing movements, whereas with the single step movement hitherto used, new ribbon surface would be presented to the said type only once every fifteen or more printing operations. In practice it has been found, as already indicated, that where as much as approximately fifteen printing operations are produced, some of the printed matter on a printed sheet will be much dimmer or lighter than other portions 100 105 110 115 120 125

thereof, thereby producing a very great unevenness in the printing of any particular sheet. It has been found that with the improved feed mechanism whereby the ribbon feed movement is increased or accelerated, the printing on any particular sheet will be uniform and as this is obvious, it is highly important in the reproduction of duplicates.

Moreover, the device described may with very slight change and with very small cost be incorporated in duplicating or reprinting machines either in the initial process of manufacture or as an attachment to machines already in use. Also from what has been said, it will be understood that the invention described is capable of various modifications within the scope of the invention herein disclosed and claimed.

What I claim is:

1. In a machine of the class described wherein a ribbon and co-operating type are employed to produce the printing actions, means for intermittently bringing the type and ribbon into printing operation of a print-receiving sheet, and means for automatically producing a plurality of ribbon-feeding movements between successive printing operations.

2. In a machine of the class described, a rotary type-equipped segment, a ribbon extended over the type, ribbon rolls rotatable with said type segments, and automatic machine-actuated ribbon-feeding mechanism constructed and arranged to impart a plurality of ribbon feeding-movements to said rolls and ribbon between successive printing operations.

3. In a machine of the class described, a rotary type-equipped segment, a ribbon extended over the type, ribbon rolls rotatable with said type segments, pawl and ratchet ribbon-feeding devices operative on said ribbon rolls, a reciprocating pawl carrier, and a plural-acting cam operative to impart a plurality of operating movements to said pawl carrier between successive printing operations.

4. In a machine of the class described, a rotary type-equipped segment, a ribbon extended over the type, ribbon rolls rotatable with said type segments, ratchet wheels connected to the respective ribbon rolls, pawls co-operating with the respective ratchet wheels, a reciprocating pawl carrier and pawls being carried with said rotary type segment, and a cam fixed on the machine frame and having a plurality of cam-acting portions operative on said pawl carrier to impart thereto a plurality of complete ribbon-feeding movements between successive printing operations.

5. The structure defined in claim 4 in which the ratchet wheels and pawls co-operating with the different ribbon rolls arranged for

operation one at a time and for reverse ribbon-feeding movements.

6. The structure defined in claim 4 in which said cam is an element formed independently of but attached to the main frame.

7. The structure defined in claim 4 in which said cam is operative on said pawl-carrier throughout the printing movement to hold the same against ribbon-feeding movement.

8. The structure defined in claim 4 in which said pawl carrier is guided on fixed machine elements for straight-line movement radiating from the axis of rotation of said type segment.

9. The structure defined in claim 4 in which said cam plate has a profile cam-way extending throughout approximately 180 degrees concentric to the axis of rotation of said type segment and in the other 180 degrees has a plurality of inwardly and outwardly extended cam surfaces, said pawl carrier having a laterally projecting stud that works in said cam-way.

In testimony whereof I affix my signature.

PERCY R. SEWARD.
